UNITED STATES PATENT OFFICE.

JAMES WILLIAM THOMAS CADETT, OF ASHTead, ENGLAND.

CARBURETER.

1,165,224.

Specification of Letters Patent. Patented Dec. 21, 1915.

Application filed July 23, 1913. Serial No. 780,789.

To all whom it may concern:

Be it known that I, JAMES WILLIAM THOMAS CADETT, a subject of the King of Great Britain, residing at Ashtead, Surrey, England, have invented new and useful Improvements Relating to Carbureters for Internal-Combustion Engines, of which the following is a specification.

This invention relates to carbureters of the type in which the petrol jet, when once set, is of constant area, and further is situated in a spray chamber or air duct of fixed dimensions for any one carbureter, as distinct from those wherein the area of the petrol jet is varied during running for purposes of control.

The object of this invention is to provide in such carbureters improved means for efficiently spraying the liquid fuel or the mixture of air and fuel passing to the engine, especially in the condition where partial throttling of the mixture of air and fuel is taking place.

According to my invention, the fuel nozzle or petrol jet is arranged in an air-duct through which the whole of the air supplied to the carbureter passes, the fuel nozzle being at such a distance from the throttle that the suction at the jet is not materially influenced by the proximity of the throttle opening. By this it is meant that, for any amount of air passing through the air-duct in unit time according to the opening of the throttle, the velocity of the air passing the petrol jet is materially that of this amount of air passing the jet in the said air duct of fixed dimensions in the same time. Were the throttle too close to the jet, the increasing velocity of the air approaching the throttle opening, especially in the partially or nearly closed position, would render the suction at the nozzle greater than the value corresponding to the degree of throttle-opening. From the nozzle arranged at such a position that the suction at the jet is not materially influenced by the proximity of the throttle opening the fuel is carried to the throttle-opening, where the velocity of the air is a maximum and consequently the spraying is most active, by means of a conveying device, such as a conical needle, rod or the like, leading to said throttle-opening, for example from the needle of a needle-valve controlling the outlet of fuel at said nozzle. In general practice the length of such conveying needle or rod, for a 20 to 40

H. P. engine, may be $\frac{1}{2}$ in., but considerable variations may be made according to the size of the carbureter. In order that the said conveying device shall always conduct the fuel to the point at which the spraying is most active, a throttling device is employed of the kind known *per se*, wherein the place at which the throttling is most active does not alter its position during adjustment of the throttle; for example, it may consist of two notched plates movable toward and away from each other, or of an iris-diaphragm throttle, or the like. It is preferred to use one nozzle for conveying fuel into the carbureter. Several nozzles may, however, be used if required. Instead of an extension of the adjusting needle, a device not connected to the adjusting needle may be provided, for instance, a fine wire or wires or a capillary tube or tubes extending from the jet to the throttle. All that is requisite is that the conveying device should extend from the center of the throttle or from a point proximate thereto into or sufficiently close to the jet so that the liquid fuel can wet such device or make contact with it. I may provide a main air inlet valve preferably of the gravity type or a valve controlled by a spring or dash-pot or both on the side of the jet away from the engine. Both of these forms of air inlet valve are known *per se*.

Figures 1 and 2 of the accompanying drawings show in plan and sectional elevation respectively a diagrammatic representation of an embodiment of my invention. Fig. 3 is a sectional elevation illustrating two modifications. Figs. 4 and 5 are plan views of the two modifications to which the elevation in Fig. 3 is common.

An extension *a* on the adjusting needle *b* of the jet *c* from the float chamber or other constant level device is arranged to extend from the jet orifice to the center of the throttle opening. The throttle which I prefer to employ is of the sliding plate type and consists essentially of two plates *d*, *e* provided with extensions *f*, *g* whereon rack teeth *f'*, *g'* are cut so as to mesh with the throttle control pinion *h*. It will be seen that rotation of the pinion causes the plates to move in opposite directions, so that holes *i*, *j*, formed therein may be brought into coincidence to give full throttle opening or moved so as to overlap more or less to give varying grades of closed throttle and that

the movement takes place in such a way that the extension *a* is always directed to the center of the area opening. To render more sensitive the throttle adjustment at positions 5 approaching that of closed throttle, I form *V* or equivalent notches *k* in the edges of the holes *i*, *j*, and chamfer the edges of the notches as indicated at *m*. To maintain the bearing surfaces of the plates in substantially 10 gas-tight contact, I provide a pressure plate *n* controlled by flat springs *o* or helical or other springs so as to keep the throttle plates and the separate top plate *p* all pressed up against the outer cover *q*.

15 By the above I provide directing or conveying means for carrying the liquid fuel from the orifice of the spray jet into the region or position in which spraying can be effected most actively and this without alteration 20 to the velocity (and hence to the suction effect) of the air flowing past the spray jet.

In a modification illustrated in Fig. 3 I have shown a group of thin rods or capillary tubes *r* in lieu of the single rod *a* in Figs. 25 1 and 2. These rods or capillary tubes are supported independently of the needle *b* for example by means of a cross bar *s*. In the case of capillary tubes they must be at 30 such a distance from the jet aperture as to prevent any suction through the capillary tubes from materially affecting the suction in the space around the jet which space is of fixed dimensions. The capillary tubes *r* are shown in plan in Fig. 4, and the rods *r'* in Fig. 5.

In the case where a jet is used of definite or suitable size and not provided with a regulating needle for initial setting, the directive device may be brought from the 40 throttle opening and extended sufficiently close to the jet, as shown in Fig. 3, so that with the minimum suction required the liquid fuel will make contact with the needle

and be conveyed by capillary attraction or 45 surface tension or attraction to the throttle opening. The throttle opening is placed at such a distance from the jet as is found not to materially influence the suction at the jet. If too far away the liquid fuel would not all 50 be carried into the throttle opening by the extension of the needle when the throttle is nearly closed and the engine working very slowly. The best distance is found by trial, the range of suitable distance varying 55 according to the size of the carburetor and gravity and surface tension of the liquid fuel. The range admits of considerable variation. I find that a jet in an air-duct of one inch bore works well with the throttle 60 opening about half an inch from the jet. I do not confine myself however to any specific distance as it can be varied considerably without departing from the essential feature 65 of this invention.

What I claim is:

A spray carburetor for internal combustion engines, comprising in combination, a casing having a single air-duct of fixed dimensions through which passes the whole of 70 the air supplied to the carburetor, a nozzle arranged in said air duct, a throttle for the mixture of air and fuel, said throttle and the walls of said air-duct being arranged at such a distance from the nozzle that the 75 suction at the jet is not materially influenced by the proximity of the throttle opening, the opening and closing of which throttle proceeds in such a way that the center of opening is at the same point in all positions 80 of throttling, and a fuel conveying device which extends from the nozzle to the center of said throttle opening for the purpose set forth.

JAMES WILLIAM THOMAS CADETT.
